UNITED STATES PATENT OFFICE.

WILLIAM J. DRISCOLL, OF BOSTON, MASSACHUSETTS.

DISPENSER.

1,194,487.

Specification of Letters Patent. Patented Aug. 15, 1916.

Application filed March 29, 1913. Serial No. 757,521.

To all whom it may concern:

Be it known that I, WILLIAM J. DRISCOLL, a citizen of the United States, and a resident of Boston, county of Suffolk, and State 5 of Massachusetts, have invented an Improvement in Dispensers, of which the following description, in connection with the accompanying drawings, is a specification, like characters on the drawings representing 10 like parts.

This invention relates to dispensers for liquids.

One of the objects of the invention is to provide a dispenser which shall be of simple 15 construction and efficient in operation.

The various features of my invention will best be understood from the following description taken in connection with the accompanying drawings of a dispenser embodying one form of my invention and selected for the purpose of illustration, the scope of the invention being more particularly pointed out in the appended claims.

In the drawings: Figure 1 is a front elevation of an apparatus embodying a preferred form of the present invention; Fig. 2 is a vertical section on line 2—2 of Fig. 5; Fig. 3 is a side elevation of the apparatus shown in Fig. 1; Fig. 4 is a horizontal section taken on line 4—4 of Fig. 1; Fig. 5 is a plan view of the apparatus shown in Fig. 1; Fig. 6 is a vertical section on line 6—6 of Fig. 1; Fig. 7 is a detail of the connection between the counter wheels and their operating shaft.

In the accompanying drawings, the invention is shown as embodied in an apparatus intended more particularly for dispensing beverages. The body 2 of the apparatus may be supported in any suitable manner as, for example, upon legs 4. In the body 2 there are provided a chamber 6 and two containers 8 and 10. Intermediate the containers 8 and 10, there is provided a valve. As shown in Figs. 2, 4 and 6, the rotary core 12 of the valve is provided with two recesses 14 and 16 extending from the periphery of said core inwardly and separated by the preferably curved partition 18. The recess 16 communicates at all times with the passage 20 of the discharge nozzle 22 by means of a passage 24. A circular plate 25 terminating in a handle 26 is attached in any suitable manner as by screws 25' 25', Fig. 2, to the exposed upper surface of the core 12 whereby to rotate said core.

With the core in the position shown in

Figs. 2 and 4, the recess 16 is in communication with a passage 28 leading from the container 8, while the recess 14 is in communication with passages 30 and 32 leading from chamber 6 and container 10, respectively. It will thus be seen that in this position of the parts, liquid contained in the chamber 6 will flow through the passage 30, recess 14 and passage 32 into the container 10, while any liquid contained in the container 8 will be free to flow out of said container through the passages 28 and 24 into the passage 20 of the nozzle 22 and be discharged from the apparatus. By turning the valve core 12 contra-clockwise, the recess 14 may be brought into communication with the passages 28 and 30 of the container 8 and chamber 6, respectively, and the recess 16 into communication with the passage 32 leading from the container 10. In this position, the liquid which had previously flowed from the chamber 6 into the container 10 will be discharged from the latter through the passages 32 and 24 and the nozzle 22, and liquid will simultaneously flow from the chamber 6 through the passage 30, recess 14 and passage 28 into the container 8. It will thus be seen that in the present apparatus one container is being replenished while the other is being discharged and that one container may be always provided with liquid ready to be dispensed.

It is desirable in apparatus of this kind that successive dispensing operations can take place in rapid succession. To this end, it is necessary that the discharge from one container and the replenishing of the other shall be effected rapidly, and the present invention contemplates the provision of means to this end. It will be noted that the passages 30, 32 and 28 are of relatively large diameter and that their length corresponds to the full height of the chamber 6 and of the containers 10 and 8, and that the recess 14 represents a relatively large section of the core 12 of the valve and that its height is equal to the full height of the passages 28, 30 and 32. It will thus be seen that the replenishing of a container will take place very rapidly, the operation being practically instantaneous. It will also be noted that the recess 16 represents a large section of the core 12 and that its height is equal to the height of the passages 28 and 32. Also that the passages 24 and 20 are very capacious, so that the discharge of the contents of a container is also effected very rapidly.

In machines of this kind, where one container is being replenished while the other is discharging, this operation being effected through a common valve, it might happen 5 that unless the replenishing of a container take place as rapidly as its discharge, the operation of the valve as soon as the discharge from one container is completed may result in that container which is being replenished, while the other is being discharged, not receiving its full quantity, so that upon reverse movement of the valve the full quantity called for will not be dispensed. The present invention contemplates means 10 to meet this difficulty and to this end, as one form of means for this purpose, the capacity of the passages through which the containers 8 and 10 are replenished from the chamber 6 and that of the passages through 15 which said containers are discharged are so proportioned relatively that the discharging operation requires a little more time than the replenishing operation. As a result, the operator can reverse the valve just as soon 20 as the discharge of the contents of a container has taken place without any danger that the other container will not have been replenished to the extent desired. This is a great advantage as it enables the apparatus 25 to be operated very rapidly, the dispensing operations following each other in unbroken succession if necessary without any danger that the proper quantity will not be dispensed in every instance. No wait between 30 successive dispensing operations is required. 35

The bottom surface 34 of the containers 8 and 10 and that of the passages 28 and 32 will preferably be inclined downwardly toward the valve so that the full quantity will 40 be discharged from said containers and there will be no drip, see Fig. 2. The bottom surface 36 of the chamber 6 may also incline downwardly toward said valve.

The containers 8 and 10 are closed in any 45 suitable manner herein by two threaded plugs 38, 38 provided with recesses 40 in their upper surfaces. By introducing any suitable implement into said recesses, said plugs may be readily unscrewed and removed to give access to said containers for 50 cleansing or any other purpose and as readily replaced. Suitable vents may be provided for the containers 8 and 10, said vents herein consisting of short tubes 42 closed at 55 their upper ends, provided with lateral openings and screw-threaded or otherwise secured in circular openings passing through the top walls of the passages 28 and 32.

The core 12 of the valve is held in position 60 in the valve chamber by rods 44 rotatably mounted in vertically disposed recesses 46 provided in bosses disposed at either side of the valve chamber and preferably integral with the walls of the latter. 65 Said rods are each provided with a laterally

projecting head 48 adapted to overlie the upper surface of the handle plate 25. Springs 50 surrounding said rods in the lower enlarged portions of said recesses 46 press with their upper ends against abutments 52 in said recesses and downwardly upon pins 54 passing through said rods 44 adjacent their lower ends, said springs thus tending to draw the laterally projecting portions of the heads 48 of said rods downwardly into contact with the upper surface of the plate 25. 70 75

The beverage or other fluid to be dispensed may be introduced in any suitable manner into the chamber 6. Said chamber may be 80 connected directly to the receptacle containing the beverage or liquid. For example, if coffee is to be dispensed, the coffee urn in which the coffee is prepared may be connected directly with said chamber 6 so as to 85 communicate therewith or said apparatus may be applied directly to the urn for that purpose.

It is often desirable to dispense beverages or other liquids from the bottle or other receptacle in which they are originally put up or received. Thus it may be desirable to dispense whisky or other liquors from the original bottle, or milk or cream from the original jar, and the present invention contemplates means whereby this is rendered possible. To this end, there may be provided in the top wall of the chamber 6 a circular opening having its walls screw-threaded to receive a screw-threaded circular 90 disk-shaped plug 56. Recesses 57, 57 may be provided in the plug to facilitate its removal by means of a suitable implement. This plug 56 is provided with a central opening herein circular for receiving the reduced 95 circular portion 58 of what may be conveniently termed a socket member 60, the shouldered portion 62 of which may rest upon the upper surface of the top wall of the chamber 6, (see Fig. 6). The upper enlarged portion of said socket member 60 is 100 preferably provided with an inner rubber sleeve 62^a. This sleeve has a circular perforation which registers with a similar circular perforation provided in the wall of the 105 socket member 60 and into which there is screw-threaded a metal plug 64, said plug being preferably screwed in sufficiently to have its inner face flush with the inner surface of the rubber sleeve 62^a. There are 110 provided in the walls of the rubber sleeve 62^a and of the socket member 60, respectively, two registering circular openings 115 adapted to receive a plug 66 which is screw-threaded into the wall of a circular opening 120 provided in a sustaining member 68 suitably mounted on the frame of the machine. 125 130

In practice the screw-threaded plug 66 having been unscrewed sufficiently to withdraw it from engagement with the opening 130

provided in the wall of the socket member 60, said socket member is withdrawn from the apparatus and is slipped on over the neck of the bottle or of the receptacle containing the liquid to be dispensed. The socket member 60 with the neck of the bottle therein is then replaced in the apparatus in the position shown in Fig. 6, the bottle being thus reversed and a part of the contents 10 flowing into the chamber 6, the flow being checked when the level of the liquid in the chamber 6 rises to the level of the lower open end of the circular portion 58 of the socket member 60 as will be readily understood. 15 The plug 66 is now screwed in inwardly until the neck 70 of the bottle is firmly clamped in said socket member 60. The plug 64 prevents the rubber sleeve 62^a from yielding in response to the clamping action 20 of the plug 66, and as the neck of the bottle is a close fit in the rubber sleeve the connection of the bottle with the socket member 60 is substantially air-tight.

It will be apparent that the sustaining 25 members 68 and plugs 64 and 66 might be dispensed with, but they exemplify a convenient means of securing the bottle in place in the apparatus so that it and its contents cannot be tampered with, the plugs 64 and 30 66 being to this end provided with openings 72, 74 to be engaged by a correspondingly constructed key, whereby said plugs can be turned. Disk-shaped plugs having different size openings and socket members of different 35 sizes may be substituted for the disk-shaped plug 56 and socket member 60, respectively, to enable receptacles of different sizes to be used.

The invention may include means for varying or regulating the amount of liquid delivered to the container. One convenient form of such means will now be described.

It will be apparent that in the form of the invention illustrated, the liquid will rise 45 in the containers 8 and 10 to the level of the lower edge of the circular portion 58 of the socket member 60 and no higher. Hence by raising and lowering the socket member 60, the amount of liquid delivered to the containers 8 and 10 and dispensed by the apparatus can be regulated or varied as desired. To this end, the sustaining member 68 is provided with two projecting lugs 76, Fig. 5, in which are secured, as by nuts 78, 55 the upper ends of two rods 80 rigidly joined at their lower ends by a cross-head 82, Fig. 1. To the under side of this cross-head are pivoted at 84 the ends of two links 86 having their other ends pivoted at 88 to nuts 90, 60 92 which are in screw-threaded engagement with right-handed and left-handed threads 94, 96, respectively, of a screw 98 mounted for rotation in two boss bearings 100 projecting from the inner faces of the two diametrically opposed legs 4 of the machine.

Said screw is secured against longitudinal movement in said boss bearing in any suitable manner. It will be apparent that by turning said screw 98 in one direction, the nuts 90, 92 will be caused to approach each other and the socket member 60, with the receptacle supported thereby, will be raised, while by turning said screw 98 in the opposite direction, the nuts 90, 92 will be separated from each other and said socket member and receptacle lowered. Any suitable means may be provided to rotate said screw, but in the present instance, in order to prevent its operation by unauthorized persons, the exposed end 102, see Fig. 3, of the screw 80 70 75 80 85 90 95 100 105 110 115 120 125 130 98 is provided with recesses 104 constructed and arranged to receive the same key that is used for turning the plugs 64, 66, so that said key may be used for operating said screw as well. To facilitate the vertical adjustment of the socket member 60 to cause the amount of liquid desired to flow into the container 8 or 10 and be dispensed therefrom, one of the rods 80 may be provided with a scale 106, as shown in Fig. 1, divided into ounces and fractions thereof, for example, and a fixed index 108 attached in any suitable manner to the frame of the apparatus may be provided to coöperate with said scale, which latter will be graded in such manner that when, in raising or lowering the socket member 60, a division of said scale is brought into coincidence with said fixed index 108, the measure or amount of fluid marked opposite said division on said scale will be delivered to the container.

If desired, vertically extending longitudinal openings 110 may be provided in the walls of the containers 8 and 10, said openings being closed by glass windows to enable 105 the height of the fluid contained in a container to be observed.

Preferably, means herein exemplified by a counter will be provided to indicate or register the number of portions dispensed by the apparatus. Such a counter is shown in Figs. 5 and 6 as mounted in a bracket 112 secured to the upper surface of the body of the apparatus, as by screws 113, and having its arms 114 projecting forwardly over 115 the plug 12. Said counter comprises the usual wheels 116 serving to indicate the units, tens, hundreds, thousands and tens of thousands, each provided upon its periphery with the numerals 1, 2, 3, 4, 5, 6, 7, 8, 9, 0. All of said wheels excepting the unit wheel, are loosely mounted on a shaft 118, Fig. 7, mounted in bearings provided in said arms 114 of the bracket 112. The unit wheel is rigidly mounted on said shaft. The 120 ends of the shaft 118 project through the arm 114 and are each provided outside of the adjacent arm with a gear wheel 120 loosely mounted on said shaft. Each of the gears 120 is provided with a lateral 130

recess 122, see Fig. 7, adapted to receive a ratchet wheel 124 rigidly mounted on the shaft 118. Within said recess 122, there is pivoted to the gear 120 at 126 a pawl 128 maintained in engagement with the teeth of the ratchet 124 by a spring 130 attached to the gear 120 at 132 within the recess 122.

The above-described construction is the same in the case of both gears 120 and from 10 the description given taken in connection with Figs. 5 and 7, it will be apparent that when either gear 120 is rotated in a clockwise direction, its pawl 128 will, by its engagement with the ratchet 124, rotate the latter and the shaft 118 clockwise, but that when either gear is rotated contra-clockwise, its pawl 128 will slide over the teeth of the ratchet 124 which will be held against rotation by a spring pressed locking 15 pawl 134 pivoted to the adjacent face of the 20 arm 114 of the bracket 112.

For rotating the gears 120 two sets of rack teeth 136, Fig. 1, each set consisting of three teeth, are provided upon the upper surface 25 of the handle plate 25, one beneath each of the gear wheels 120 so as to engage the latter and rotate them as the handle 26 is oscillated. With the parts in the position shown in Fig. 5, if the handle 26 be swung to the 30 right, the three rack teeth 136 beneath the left hand gear 120 will rotate the latter clockwise and with it the shaft 118 and unit wheel of the counter, while the three rack teeth below the right hand gear 120 in said 35 figure will rotate the latter contra-clockwise without causing any operation of the shaft 118. If the handle 26 be now swung back into the position shown in Fig. 5, the three rack teeth 136 below the right hand gear 120 40 will rotate the latter clockwise thus actuating the shaft 118 and the unit wheel of the counter, while the rack teeth beneath the left hand gear wheel 120 will rotate the latter contra-clockwise without operating the shaft 45 118. As the ratchet wheel 124 is provided with thirty teeth and three rack teeth are provided for rotating each of the gears 120, it will be apparent that each time that either 50 gear is rotated clockwise the unit wheel of the counter will be turned one-tenth of a complete rotation.

It is deemed unnecessary to describe the connection between the various counter wheels whereby each counter wheel in 55 effecting its tenth increment of a complete rotation rotates the one of the next highest denomination an increment equal to one-tenth of a complete rotation. Such arrangements are well known and require no 60 explanation here to be fully understood. The counter wheels are contained in a casing 138 provided with a glass window 140 through which the numerals on the counter wheels are clearly observable. Preferably, 65 the sets of rack teeth 136 are so disposed

70 relatively to the wheels 120 that the counter will be caused to register by any movement of the handle 26 sufficient to establish communication between the chamber 6 and either of the containers 8 or 10.

75 It is preferable that when movement of the handle 26 has been initiated in either direction, reverse movement of the handle be prevented until it has completed its full stroke or until the valve has been turned sufficiently to establish communication between the container which is to be discharged and the nozzle 22 and also sufficiently to cause the counter to register. Means are accordingly provided to that end, said means 80 in the illustrative embodiment of the invention shown comprising rack teeth 142 provided on the periphery of the handle plate 25, see Fig. 5. A pawl 144 is pivoted at 146 on the base of the bracket 112, the swinging 85 movement of said pawl in either direction being limited by stops 148, 150. The distance from the pivot 146 to the operative end of the pawl is greater than the distance from said pivot to the base of the space between 90 any two of the teeth 142 when said space is directly opposite said pivot. As a result, the parts being in the position shown in Fig. 5, if the handle 26 be swung contra-clockwise, the rack teeth 142 will engage the pawl 144 95 which will thus incline slightly to the left, thus permitting free movement of the handle 26 contra-clockwise but preventing by its engagement with said rack teeth any reverse movement of said handle. When in the continued movement of the handle 26 in a contra-clockwise direction, the rack teeth 142 have passed out of engagement with the pawl 144, reverse movement of the handle, that is to say, movement in a clockwise direction, is 100 105 no longer prevented. In such movement, the rack teeth 142 engage the pawl from the other side and said pawl being thus inclined to the right permits free movement of the handle 26 in a clockwise direction, but so 110 long as the pawl is in engagement with the rack teeth, movement of the handle 26 contra-clockwise will be prevented and can only take place after the handle has been moved sufficiently far in a clockwise direction to 115 carry the rack teeth 142 out of engagement with the pawl 144.

120 By unscrewing screws 113, Fig. 5, the counter supporting arm 114, Fig. 6, can be readily removed, and then on removing the screws 25' 25', Fig. 2, the plate 25 can be withdrawn from under the overlapping edges of the heads 48 of rods 44. As these heads 48 do not overlap the edges of the core 12, the latter can now be removed to give 125 access to the valve chamber and adjacent parts and to said core. It will thus be seen that all parts of the apparatus are readily accessible for cleansing or for any other purpose.

It will be apparent that if it is not desired to vary the quantity of liquid dispensed, the reduced circular portion 58 of the socket member 60 may be shortened so 5 that it shall terminate substantially flush with the lower surface of the plug 56 or of the inner surface of the top wall of the containers 8 and 10. In such case, and also in the case where the chamber 6 is caused to 10 communicate directly with a source of supply, the containers 8 and 10 will always be filled to their full capacity. Any size container may be used in accordance with the present invention. It will be apparent that 15 a tube communicating with any continuous source of supply of the liquid to be dispensed could be inserted in the socket 6 in the place of the neck 70 of a bottle.

While vents 42, 42 have been provided in 20 the illustrative embodiment of the invention shown, such vents are not essential as, owing to the fact that the top walls of the containers 8 and 10 are on a level with the top walls of the chamber 6, any air contained in the containers 8 or 10 can escape 25 freely, even when the containers are filled to their full capacity as will be apparent to those skilled in the art without further explanation. If desired, the top walls of the 30 containers 8 and 10 may be caused to incline slightly upward toward their point of junction with the plug 12 to facilitate such escape of the air.

It is not deemed necessary to give any 35 further explanation of the mode of operation of the specific apparatus shown as such operation will be perfectly clear to those skilled in the art from the description above given of the apparatus itself.

40 It will be apparent that it is not indispensable that all of the features of the invention be used conjointly since they may be used to advantage separately in various combinations and sub-combinations. It will 45 also be understood that while the invention is herein described as embodied in the details illustrated, it is not to be considered as circumscribed or limited to these details, or any of them, but it may be variously modified 50 within the true scope of the invention which is definitely set forth by the claims.

Claims:

1. In a dispensing apparatus, in combination, an adjustable member provided with a 55 passage therethrough adapted to receive the open end of a receptacle containing the fluid to be dispensed, the lower end of said member extending into a fluid chamber provided with an outlet passage; sustaining means 60 for said member; means for securing said member to said sustaining means and the receptacle to said member; two containers each provided with a passage leading therefrom; a movable valve member provided 65 with two chambers, one communicating with

said outlet passage and adapted to communicate with the passage leading from either one of said containers and the other communicating with the discharge opening of the valve and adapted to communicate 70 with the passage leading from either container; means for moving said valve member to cause said first named valve chamber which communicates with said outlet passage to communicate with the passage leading from either one of said containers and to cause the other valve chamber which communicates with the discharge opening of the valve to communicate with the passage leading from the other container; a 75 counter; means for operating the latter by movement of said valve member; means for varying the position of the adjustable member to vary the amount of fluid to be dispensed; and indicator means to indicate the 80 amount of fluid to be dispensed.

2. In a dispensing apparatus, in combination, an adjustable member provided with a passage therethrough adapted to receive the open end of a receptacle containing the fluid 90 to be dispensed, the lower end of said member extending into a fluid chamber provided with an outlet passage; sustaining means for said member; means for securing said member to said sustaining means and the receptacle to said member; two containers each provided with a passage leading therefrom; a movable valve member provided with two chambers, one communicating with said outlet passage and adapted to communicate 95 with the passage leading from either one of said containers, and the other communicating with the discharge opening of the valve and adapted to communicate with the passage leading from either container; means for moving said valve member to cause said first named valve chamber to communicate with the passage leading from either one of said containers and with the passage leading from said fluid chamber 100 and to cause the other valve chamber to communicate with the passage leading from the other container; a counter; means for operating the latter by movement of said valve member; and means for varying the position of the adjustable member to vary the 105 amount of fluid to be dispensed.

3. In a dispensing apparatus, in combination, an adjustable member provided with a passage therethrough adapted to receive the 120 open end of a receptacle containing the fluid to be dispensed, the lower end of said member extending into a fluid chamber provided with an outlet passage; sustaining means for said member; means for securing said member to said sustaining means and the receptacle to said member; two containers each provided with a passage leading therefrom; a movable valve member provided with two 125 chambers, one communicating with said outlet passage and adapted to communicate with the passage leading from either one of said containers, and the other communicating with the discharge opening of the valve and adapted to communicate with the passage leading from the other container; a counter; means for operating the latter by movement of said valve member; and means for varying the position of the adjustable member to vary the amount of fluid to be dispensed.

- let passage of said fluid chamber and adapted to communicate with the passage leading from either one of said containers, and the other communicating with the discharge opening of the valve and adapted to communicate with the passage leading from either container; means for moving said valve member to cause said first named valve chamber to communicate with the passage leading from either one of said containers and with the outlet passage of said fluid chamber and to cause the other valve chamber to communicate with the passage leading from the other container; means for varying the position of the adjustable member to vary the amount of fluid to be dispensed; and indicating means to indicate the amount of fluid to be dispensed.
4. In a dispensing apparatus, in combination, an adjustable member provided with a passage therethrough adapted to receive the open end of a receptacle containing the fluid to be dispensed, the lower end of said member extending into a fluid chamber provided with an outlet passage; sustaining means for said member; means for securing said member to said sustaining means and the receptacle to said member; two containers each provided with a passage leading therefrom; a movable valve member provided with two chambers, one communicating with said outlet passage and adapted to communicate with the passage leading from either one of said containers, and the other communicating with the discharge opening of the valve and adapted to communicate with the passage leading from either container; means for moving said valve member to cause said first named chamber of said valve member to communicate with the passage leading from either one of said containers and to cause the other chamber of said valve member to communicate with the passage leading from the other container; a counter; means for operating the latter; means for varying the position of the adjustable member to vary the amount of fluid to be dispensed; and indicating means to indicate the amount of fluid to be dispensed.
5. In a dispensing apparatus, in combination, a member provided with a passage therethrough adapted to be connected to a source of fluid supply, one end of said member extending into a fluid chamber provided with an outlet passage; sustaining means for said member; means variably to adjust the position of said member; means for securing said member to said sustaining means and the receptacle to said member; two containers each provided with a passage leading therefrom; a movable valve member provided with two chambers, one communicating with said outlet passage and adapted to communicate with the passage leading from either one of said containers, and the other

communicating with the discharge opening of the valve and adapted to communicate with the passage leading from either container; and means for moving said valve member to cause said first named chamber of said valve member to communicate with the passage leading from either one of said containers and to cause the other chamber of said valve member to communicate with the passage leading from the other container.

6. In a dispensing apparatus, in combination, sustaining means for a receptacle containing the fluid to be dispensed, the open end of said otherwise closed receptacle extending into a fluid chamber provided with an outlet passage; means variably to adjust the position of said sustaining means; a plurality of containers each provided with a passage leading therefrom; valve means including two separate ways, one of which communicates with the discharge opening of the apparatus and is adapted to communicate with the passage leading from any one of the containers, and the other of which communicates with said outlet passage and is also adapted to communicate with the passage leading from any one of the containers; and means for operating said valve means to cause that valve-way which communicates with the discharge opening of the apparatus to communicate with the passage leading from one container, and to cause the other valve-way which communicates with said outlet passage to communicate with the passage leading from another container.

7. In a dispensing apparatus, in combination, a member provided with a passage leading from an otherwise closed receptacle for the fluid to be dispensed, the open end of said member extending into a fluid chamber provided with an outlet passage; means variably to adjust the position of said member; a plurality of containers each provided with a passage leading therefrom; valve means including two separate ways; one of which communicates with the discharge opening of the apparatus, and the other with said outlet passage; a visible counter; and common operating means for simultaneously operating said counter and actuating said valve means to cause that valve-way which communicates with the discharge opening of the apparatus to communicate also with the passage leading from one container, and to cause the other valve-way that communicates with said outlet passage of the fluid chamber to communicate also with the passage leading from another container.

8. In a dispensing apparatus, in combination, an adjustable member provided with a passage therethrough and adapted to receive the open end of a receptacle containing the fluid to be dispensed, the lower end of said member extending into a fluid chamber provided with an outlet passage; sustaining

- means for said member; means for securing said member to said sustaining means and the receptacle to said member; a plurality of containers each provided with a passage 5 leading therefrom; valve means including two separate ways, one of which communicates with the discharge opening of the apparatus, and the other with said outlet passage; means for operating said valve means 10 to cause that valve-way which communicates with the discharge opening of the apparatus to communicate also with the passage leading from one container, and to cause the other valve-way which communicates with said outlet passage to communicate also with the passage leading from another container; and means for varying the position of the adjustable member to vary the amount of fluid to be dispensed.
- 20 9. In a dispensing apparatus, in combination, an adjustable member provided with a passage therethrough and adapted to receive the open end of a receptacle containing the fluid to be dispensed, the lower end 25 of said member extending into a fluid chamber provided with an outlet passage; sustaining means for said member; means for securing said member to said sustaining means and the receptacle to said member; 30 a plurality of containers each provided with a passage leading therefrom; valve means including two separate ways, one of which communicates with the discharge opening of the apparatus, and the other with said 35 outlet passage; means for operating said valve means to cause that valve-way which communicates with the discharge opening of the apparatus to communicate also with the passage leading from one container, and 40 to cause the other valve-way which communicates with said outlet passage to communicate also with the passage leading from another container; means for varying the position of the adjustable member to 45 vary the amount of fluid to be dispensed; and indicator means to indicate the amount of fluid to be dispensed.
10. In a dispensing apparatus, in combination, a plurality of containers each provided with a port; a fluid supply chamber provided with a discharge opening; valve means including two separate ways, one of which communicates with the discharge opening of the apparatus, and the other 55 with the discharge opening of said fluid supply chamber, each of said ways being adapted to communicate with the port of a container; means for operating said valve means to cause that valve-way which communicates with the discharge opening of said fluid supply chamber to communicate also with the port of a container, and to cause the other valve-way which communicates with the discharge opening of the apparatus to communicate also with the port of a container; and means for operating said valve means to cause the discharge valve-way to communicate also with the port of one container and to cause the receiving valve-way to communicate also with the port of another container.

of another container; and means for varying the amount of fluid to be dispensed by varying the level thereof in said supply chamber.

11. In a dispensing apparatus, in combination, a plurality of containers each provided with a passage leading therefrom; valve means including two separate ways, one of which communicates at all times with the discharge opening of the apparatus and the other at all times with a fluid supply chamber, each of said ways being adapted to communicate with the passage leading from any one of the containers; means for operating said valve means to cause that valve-way which communicates with the discharge opening of the apparatus to communicate also with the passage leading from one container, and to cause the other valve-way which communicates with said supply chamber to communicate also with the passage leading from another container; means for varying the amount of fluid to be dispensed; and indicator means for indicating the amount to be dispensed.

12. In a dispensing apparatus, in combination, a plurality of containers each provided with a port; a fluid supply chamber provided with a discharge port; reciprocating valve means including two separate ways, one of which communicates at all times with the discharge opening of the apparatus and the other at all times with the discharge port of said fluid supply chamber, each of said ways being adapted to communicate with the port of only one of the containers at a time; means for reciprocating said valve means to cause that valve-way which communicates with the discharge opening of the apparatus to communicate also with the port of one container, and to cause the other valve-way which communicates with the discharge port of said supply chamber to communicate also with the port of another container; and means acting during a part of the movement of said valve means to lock the latter against reverse operation.

13. In a dispensing apparatus, in combination, a plurality of containers each provided with a port; a fluid supply chamber having a discharge port; valve means including a receiving valve-way and a discharge valve-way, said receiving valve-way communicating with the discharge port of said fluid supply chamber and said discharge valve-way communicating with the discharge opening of the apparatus, each of said valve-ways being adapted to communicate with the port of any one of the containers; means for operating said valve means to cause the discharge valve-way to communicate also with the port of one container and to cause the receiving valve-way to communicate also with the port of another container.

nicate also with the port of another container, the total capacity of the receiving valve-way, of the discharge port, of the fluid supply chamber and of the port of a container being greater than the total capacity of the discharge valve-way, of the port of a container and of the discharge opening of the apparatus.

14. In a dispensing apparatus, in combination, two containers each provided with a port; a fluid supply chamber having a discharge port; a reciprocatory valve having a receiving valve-way and a discharge valve-way, said receiving valve-way communicating with the discharge port of said fluid supply chamber and said discharge valve-way communicating with the discharge opening of the apparatus, each of said valve-ways being adapted to communicate with the port of only one of said two containers at a time; a valve operating member for reciprocating said valve to cause the receiving valve-way to communicate also with the port of a container and the discharge valve-way to communicate also with the port of the other container; a counter including two gears; a rack adapted to mesh with either of said gears and actuated by operation of said valve operating member to rotate said gears and operate said counter; and locking means acting during a portion of the operation of said valve to lock the latter against reverse movement.

15. In a dispensing apparatus, in combination, two containers each provided with a port; a fluid supply chamber having a discharge port; a reciprocatory valve having a receiving valve-way and a discharge valve-way, said receiving valve-way communicating with the discharge port of said fluid supply chamber and said discharge valve-way communicating with the discharge opening of the apparatus, each of said valve-ways being adapted to communicate with the port of only one of said two containers at a time; a valve operating member for reciprocating said valve to cause the receiving valve-way to communicate also with the port of one container and the discharge valve-way to communicate also with the port of the other container; a counter including two gears; a rack adapted to mesh with either of said gears and actuated by operation of said valve operating member to rotate said gears and operate said counter; and locking means, including a rack and pawl, rendered operative during a portion of the operation of said valve for locking the latter against reverse movement.

16. In a dispensing apparatus, in combination, two containers each provided with a port; a fluid supply chamber having a discharge port; a reciprocatory valve provided with a receiving valve-way and a discharge

valve-way, said receiving valve-way communicating with the discharge port of said fluid supply chamber and said discharge valve-way communicating with the discharge opening of the apparatus, each of said valve-ways being adapted to communicate with the port of either container; a counter; and common operating means for simultaneously operating said counter and to reciprocate said valve to cause the receiving valve-way and the discharge valve-way each to communicate also with the port of each of the containers alternately.

17. In a dispensing apparatus, in combination, a body provided with a fluid chamber provided with a discharge opening adapted to receive the discharge opening of a receptacle containing the fluid to be dispensed; a plurality of containers each provided with an opening; a valve provided with a receiving valve-way and a discharge valve-way, said receiving valve-way communicating with the discharge opening of said fluid chamber and said discharge valve-way communicating with the discharge opening of the apparatus and either of said valve-ways being adapted to communicate with the opening of a container; means for operating said valve to cause the receiving valve-way to communicate also with the opening of one of the containers and to cause the discharge valve-way to communicate also with the opening of another container; and means vertically to adjust the discharge opening of said receptacle to vary the amount of fluid to be dispensed.

18. In a dispensing apparatus, in combination, a body provided with a fluid chamber provided with a discharge opening adapted to receive the discharge opening of a receptacle containing the fluid to be dispensed; two containers each provided with an opening; a valve provided with a receiving valve-way and a discharge valve-way, said receiving valve-way communicating with the discharge opening of said fluid chamber and said discharge valve-way communicating with the discharge opening of the apparatus, each of said valve-ways being adapted to communicate with the passage leading from either container; means for operating said valve to cause the receiving valve-way to communicate also with the opening of one of said containers and the discharge valve-way to communicate also with the opening of the other container; and means vertically to adjust the discharge opening of said receptacle to vary the amount of fluid to be dispensed.

19. In a dispensing apparatus, in combination, a fluid supply chamber; a container communicating with the latter; means for discharging the contents of said container therefrom and means for varying the

- amount of fluid supplied to said container by varying the level of the fluid contained in the fluid supply chamber.
20. In a dispensing apparatus, in combination, a fluid supply chamber provided with a discharge port; a container provided with a port; a valve provided with a receiving valve-way and a discharge valve-way of different capacities, said receiving valve-way communicating with the discharge port of said fluid supply chamber and said discharge valve-way communicating with the discharge opening of the apparatus, each of said valve-ways being adapted to communicate with the port of the container; and means for reciprocating said valve to cause the receiving valve-way and the discharge valve-way thereof to communicate also alternately with the port of the container.
- 20 21. In a dispensing apparatus, in combination, a fluid supply chamber provided with a discharge port; a container provided with a port; a valve provided with a receiving valve-way and a discharge valve-way, said receiving valve-way communicating with the discharge port of said fluid supply chamber and said discharge valve-way communicating with the discharge opening of the apparatus, each of said valve-ways being adapted to communicate with the port of the container; means for operating said valve to cause the receiving valve-way and the discharge valve-way thereof to communicate also alternately with the port of the container; and means to vary the amount of fluid supplied to a container from the supply chamber by varying the level of the fluid in the latter.
- 20 22. In a dispensing apparatus, in combination, a fluid supply chamber provided with a discharge port; a container provided with a port; a valve provided with a receiving valve-way and a discharge valve-way of different capacities, said receiving valve-way communicating with the discharge port of said fluid supply chamber and said discharge valve-way communicating with the discharge opening of the apparatus, each of said valve-ways being adapted to communicate with the port of the container; means for reciprocating said valve to cause the receiving valve-way and the discharge valve-way thereof to communicate also alternately with the port of the container; and visible counter means operated by the operation of said valve.
- 20 23. In a dispensing apparatus, in combination, a fluid supply chamber provided with a discharge port; a container provided with a port; a valve provided with a receiving valve-way and a discharge valve-way, said receiving valve-way communicating with the discharge port of said fluid supply chamber and said discharge valve-way.
- communicating with the discharge opening 65 of the apparatus, each of said valve-ways being adapted to communicate with the port of the container; means for operating said valve to cause the receiving valve-way and the discharge valve-way thereof to communicate also alternately with the port of the container; means to vary the amount of fluid supplied to a container from the supply chamber by varying the level of the fluid in the latter; and visible counter 70 means operated by the operation of said valve.
24. In a dispensing apparatus, in combination, two containers each provided with a port; a fluid supply chamber having a discharge port; a valve adapted to be moved alternately in opposite directions and provided with a receiving valve-way and a discharge valve-way, said receiving valve-way communicating with the discharge port of 80 said fluid supply chamber and said discharge valve-way communicating with the discharge opening of the apparatus, each of said valve-ways being adapted to communicate with the port of either container; a counter; common operating means for simultaneously operating said counter and alternately to move said valve in opposite directions to cause the receiving valve-way and the discharge valve-way each to communicate also with the port of each of the containers alternately; stops to limit the movement of said valve in opposite directions; and means operative during the movement of said valve in either direction to 85 lock said valve against reverse movement, but adapted to release said valve toward the end of movement thereof in either direction thereupon to permit reverse movement 90 of said valve.
- 24 25. In a dispensing apparatus, in combination, two containers each provided with a port; a fluid supply chamber having a discharge port; a valve adapted to be moved alternately in opposite direction and provided with a receiving valve-way and a discharge valve-way, said receiving valve-way communicating with the discharge port of 95 said fluid supply chamber and said discharge valve-way communicating with the discharge opening of the apparatus, each of said valve-ways being adapted to communicate with the port of either container; a counter; common operating means for simultaneously operating said counter and alternately to move said valve in opposite directions to cause the receiving valve-way and the discharge valve-way each to communicate also with the port of each of the containers alternately; and means operative during the movement of said valve in either direction to 100 lock said valve against reverse movement, but adapted to release said valve toward the end of movement thereof in either direction thereupon to permit reverse movement 105 of said valve.
- 25 26. In a dispensing apparatus, in combination, two containers each provided with a port; a fluid supply chamber having a discharge port; a valve adapted to be moved alternately in opposite direction and provided with a receiving valve-way and a discharge valve-way, said receiving valve-way communicating with the discharge port of 110 said fluid supply chamber and said discharge valve-way communicating with the discharge opening of the apparatus, each of said valve-ways being adapted to communicate with the port of either container; a counter; common operating means for simultaneously operating said counter and alternately to move said valve in opposite directions to cause the receiving valve-way and the discharge valve-way each to communicate also with the port of each of the containers alternately; and means operative 115 during a part of the movement of said valve in either direction to lock said valve against reverse movement.
- 26 27. In a dispensing apparatus, in combination, two containers each provided with a port; a fluid supply chamber having a discharge port; a valve adapted to be moved alternately in opposite direction and provided with a receiving valve-way and a discharge valve-way, said receiving valve-way communicating with the discharge port of 120 said fluid supply chamber and said discharge valve-way communicating with the discharge opening of the apparatus, each of said valve-ways being adapted to communicate with the port of either container; a counter; common operating means for simultaneously operating said counter and alternately to move said valve in opposite directions to cause the receiving valve-way and the discharge valve-way each to communicate also with the port of each of the containers alternately; and means operative 125 during a part of the movement of said valve in either direction to lock said valve against reverse movement.

26. In a dispensing apparatus, in combination, two containers each provided with a port; a fluid supply chamber having a discharge port; a valve adapted to be moved alternately in opposite directions and provided with a receiving valve-way and a discharge valve-way, said receiving valve-way communicating with the discharge port of said fluid supply chamber and said discharge valve-way communicating with the discharge opening of the apparatus, each of said valve-ways being adapted to communicate with the port of either container; a counter; common operating means for simultaneously operating said counter and alternately to move said valve in opposite directions to cause the receiving valve-way and the discharge valve-way each to communicate also with the port of each of the containers alternately; and means operative during the movement of said valve in either direction automatically to lock said valve against reverse movement, and automatically to release said valve toward the end of its movement in either direction to permit reverse movement thereof.

27. In a dispensing apparatus, in combination, two containers each provided with a port; a fluid supply chamber having a discharge port; a valve adapted to be moved alternately in opposite directions and provided with a receiving valve-way and a discharge valve-way, said receiving valve-way communicating with the discharge port of said fluid supply chamber and said discharge valve-way communicating with the discharge opening of the apparatus, each of said valve-ways being adapted to communicate with the port of either container; a counter; common operating means for simultaneously operating said counter and alternately to move said valve in opposite directions to cause the receiving valve-way and the discharge valve-way each to communicate also with the port of each of the containers alternately; and means operative during a part of the movement of said valve in either direction automatically to lock said valve against reverse movement, but automatically to unlock said valve toward the end of the latter's movement in either direction to permit reverse movement thereof.

28. In a dispensing apparatus, in combination, two containers each provided with a port; a fluid supply chamber having a discharge port; a valve provided with a receiving valve-way and a discharge valve-way, said receiving valve-way communicating at all times with the discharge port of said fluid supply chamber and said discharge valve-way communicating at all times with the discharge opening of the apparatus, each of said valve-ways being adapted to communicate with the port of each container at a time without communi-

cating with the port of the other container; and means to reciprocate said valve to cause the receiving valve-way and the discharge valve-way each to communicate also alternately with the port of one of each of the containers alternately without communicating with the port of the other container.

29. In a dispensing apparatus, in combination, two containers each provided with a port; a fluid supply chamber having a discharge port; a valve provided with a receiving valve-way, and a discharge valve-way, said receiving valve-way communicating at all times with the discharge port of said fluid supply chamber and said discharge valve-way communicating at all times with the discharge opening of the apparatus, each of said valve-ways being adapted to communicate with the port of but one of said containers at a time; means to reciprocate said valve to cause the receiving valve-way and the discharge valve-way each to communicate also with the port of each of the containers alternately; and means operative during the movement of said valve in either direction to lock said valve against reverse movement.

30. In a dispensing apparatus, in combination, two containers each provided with a port; a fluid supply chamber having a discharge port; a valve provided with a receiving valve-way and a discharge valve-way, said receiving valve-way communicating at all times with the discharge port of said fluid supply chamber and said discharge valve-way communicating at all times with the discharge opening of the apparatus, each of said valve-ways being adapted to communicate with the port of but one of said containers at a time; means to reciprocate said valve to cause the receiving valve-way and the discharge valve-way each to communicate also with the port of each of the containers alternately; and means operative during a part of the movement of said valve in either direction to lock said valve against reverse movement.

31. In a dispensing apparatus, in combination, two containers each provided with a port; a fluid supply chamber having a discharge port; a valve provided with a receiving valve-way and a discharge valve-way, said receiving valve-way communicating at all times with the discharge port of said fluid supply chamber and said discharge valve-way communicating at all times with the discharge opening of the apparatus, each of said valve-ways being adapted to communicate with the port of but one of said containers at a time; means to reciprocate said valve to cause the receiving valve-way and the discharge valve-way each to communicate also with the port of each of the containers alternately; and means operative during the movement of

said valve in either direction automatically to lock said valve against reverse movement.

32. In a dispensing apparatus, in combination, two containers each provided with a port; a fluid supply chamber having a discharge port; a valve provided with a receiving valve-way and a discharge valve-way, said receiving valve-way communicating at all times with the discharge port of said fluid supply chamber and said discharge valve-way communicating at all times with the discharge opening of the apparatus, each of said valve-ways being adapted to communicate with the port of but one of said containers at a time; means to reciprocate said valve to cause the receiving valve-way and the discharge valve-way each to communicate also with the port of each of the containers alternately; and means operative during a part of the movement of said valve in either direction automatically to lock said valve against reverse movement.

33. In a dispensing apparatus, in combination, two containers each provided with a port; a fluid supply chamber having a discharge port; a valve provided with a receiving valve-way and a discharge valve-way, said receiving valve-way communicating at all times with the discharge port of said fluid supply chamber and said discharge valve-way communicating at all times with the discharge opening of the apparatus, each of said valve-ways being adapted to communicate with the port of but one of said containers at a time; means to reciprocate said valve to cause the receiving valve-way and the discharge valve-way each to communicate also with the port of each of the containers alternately; and means to vary the amount of fluid to be dispensed.

34. In a dispensing apparatus, in combination, two containers each provided with a port; a fluid supply chamber having a discharge port; a valve provided with a receiving valve-way and a discharge valve-way, said receiving valve-way communicating with the discharge port of said fluid supply chamber and said discharge valve-way communicating with the discharge opening of the apparatus, each of said valve-ways being adapted to communicate with the port of each container; means to reciprocate said valve to cause the receiving valve-way and the discharge valve-way each to communicate also with the port of each of the containers alternately; and means to vary the amount of fluid to be dispensed by varying the level of the fluid in the supply chamber.

35. In a dispensing apparatus, in combination, two containers each provided with a port; a fluid supply chamber having a discharge port; a valve provided with a receiving valve-way and a discharge valve-way, said receiving valve-way communicating at all times with the discharge port of said fluid supply chamber and said discharge valve-way communicating at all times with the discharge opening of the apparatus, each of said valve-ways being adapted to communicate with the port of but one of said containers at a time; means to reciprocate said valve to cause the receiving valve-way and the discharge valve-way each to communicate also with the port of each of the containers alternately; means to vary the amount of fluid to be dispensed by varying the level of the fluid in the supply chamber; and indicator means to indicate the amount of fluid to be dispensed.

36. In a dispensing apparatus, in combination, two containers each provided with a port; a fluid supply chamber having a discharge port; a valve provided with a receiving valve-way and a discharge valve-way, said receiving valve-way communicating with the discharge port of said fluid supply chamber and said discharge valve-way communicating with the discharge opening of the apparatus, each of said valve-ways being adapted to communicate with the port of each of the containers alternately; means to vary the amount of fluid to be dispensed; and indicator means to indicate the amount of fluid to be dispensed.

37. In a dispensing apparatus, in combination, a plurality of containers each provided with a port; a fluid supply chamber having a discharge port; a valve having a receiving valve-way and a discharge valve-way, said receiving valve-way communicating with the discharge port of said fluid supply chamber and said discharge valve-way communicating with the discharge opening of the apparatus, each of said valve-ways being adapted to communicate with the port of any one of the containers; means for operating said valve to cause the discharge valve-way to communicate also with the port of one container and to cause the receiving valve-way to communicate also with the port of another container, the fluid supply communications between a container and the fluid supply chamber and the communications between the discharge opening of the apparatus and a container being of different capacity.

38. In a dispensing apparatus, in combination, a plurality of containers each provided with a port; a fluid supply chamber having a discharge port; a valve having a receiving valve-way and a discharge valve-way, said receiving valve-way communicating with the discharge port of said fluid supply chamber and said discharge valve-way communicating with the discharge opening of the apparatus.

opening of the apparatus, each of said valve-ways being adapted to communicate with the port of any one of the containers; and means for operating said valve to cause the discharge valve-way to communicate also with the port of one container and to cause the receiving valve-way to communicate also with the port of another container, the communications between the fluid supply chamber and a container being of greater capacity than the communications between a container and the discharge opening of the apparatus.

39. In a dispensing apparatus, in combination, two containers each provided with a port; a fluid supply chamber having a discharge port; a valve including a receiving valve-way and a discharge valve-way, said receiving valve-way communicating with the discharge port of said fluid supply chamber and said discharge valve-way communicating with the discharge opening of the apparatus, each valve-way being adapted to communicate with the port of either container; and means for operating said valve to cause the receiving valve-way to communicate also with the port of one container and the discharge valve-way to communicate also with the port of the other container, the communications for the fluid between the fluid supply chamber and a container being of greater capacity than the communications leading from the container to the discharge opening of the apparatus.

fluid between a container and the discharge opening of the apparatus being of different capacity.

40. In a dispensing apparatus, in combination, two containers each provided with a port; a fluid supply chamber having a discharge port; a valve including a receiving valve-way and a discharge valve-way, said receiving valve-way communicating with the discharge port of said fluid supply chamber and said discharge valve-way communicating with the discharge opening of the apparatus, each valve-way being adapted to communicate with the port of either container; and means for operating said valve to cause the receiving valve-way to communicate also with the port of one container and the discharge valve-way to communicate also with the port of the other container, the communications for the fluid leading from the fluid supply chamber to a container being of greater capacity than the communications leading from the container to the discharge opening of the apparatus.

In testimony whereof, I have signed my name to this specification, in the presence of two subscribing witnesses.

WILLIAM J. DRISCOLL.
